UNITED STATES PATENT OFFICE.

WILLIAM BROWN, OF FORT CAMERON, UTAH TERRITORY.

RAILROAD-TIE.

SPECIFICATION forming part of Letters Patent No. 231,755, dated August 31, 1880.

Application filed June 12, 1880. (No model.)

To all whom it may concern:

Be it known that I, WILLIAM BROWN, of Fort Cameron, Territory of Utah, have invented a new and Improved Railroad-Tie, of 5 which the following is a specification.

The object of this invention is to provide a stronger, more durable, and economical railroad-tie.

The invention consists of a hollow iron rail-
10 road-tie, of rectangular cross-section, having a concave bottom, and having end ledges formed on its top to prevent the spreading of the rails.

Figure 1 is a perspective view of the tie with sections of rails set therein in position, and
15 Fig. 2 is a longitudinal sectional side elevation of the same.

Similar letters of reference indicate corresponding parts.

In the drawings, A represents the tie, having a concave bottom, as shown at *a*, with vertical sides and flat top, the bottom of the said tie being longer than the top and the ends thereof sloping upward and inward, as shown at *f*.

25 On the ends of the top of the tie the transverse ledges *b b* are formed, which prevent the outward spreading of the rails *B B*, that are set against them, and also lessen the strain upon the bolts *C C*, that hold the said rails 30 down in position.

The bolts *C C* are preferably spike-headed, and are entered through holes in the top of the tie and ledges *b b* and secured in place by nuts *d d*; or the said bolts *C C* may have slotted 35 ends and be secured in place by keys driven

through said slots beneath the top plate of the tie.

The ledges *b b* may be formed as part of the tie A or may be attached thereto after the tie is made. This tie A, being hollow, is of great service in serving as a conduit for water, thereby preventing "wash-outs" from heavy rains, and serving to keep the sides of the road-bed thoroughly drained. Having a concave bottom, as shown at *a*, the tie takes a firmer hold upon the ground than does a flat-bottomed tie, and is not so liable, consequently, to be twisted out of place. Doors may be placed upon its open ends, so that it may be used as a store-house for the tools of the section workmen or for other purposes. This tie, being constructed of iron, will outlast many of the best wooden ties, and consequently be a much more economical tie, although the first cost is greater. When used on road-beds where it is not required to serve the purpose of draining the said beds, the tie may be filled with earth, whereby great solidity will be imparted to the road.

Having thus described my invention, I claim as new and desire to secure by Letters Patent—

A hollow iron railroad-tie constructed substantially as herein shown and described, having a concave bottom, sloping ends, and provided with transverse ledges across its top ends, 65 as set forth.

WILLIAM BROWN.
